ATTORNEY.

UNITED STATES PATENT OFFICE.

GEORGE S. HURST, OF GLASTONBURY, CONNECTICUT, ASSIGNOR TO THE J. B. WILLIAMS COMPANY, OF GLASTONBURY, CONNECTICUT, A CORPORATION OF CONNECTICUT.

DISPLAY DEVICE.

Application filed July 27, 1923. Serial No. 654,174.

To all whom it may concern:

Be it known that I, GEORGE S. HURST, a citizen of the United States, and a resident of Glastonbury, in the county of Hartford and State of Connecticut, have invented a new and Improved Display Device, of which the following is a specification.

My invention relates more especially to the class of devices used to call attention to or explain merchandise in connection with the display thereof, and an object of my invention, among others, is to provide a device of this class that may be readily attached to dummies representing packages of merchandise or to such packages themselves and that shall comprise an attractive display medium.

One form of device embodying my invention and in the construction and use of which the objects herein set out, as well as others, may be attained, is illustrated in the accompanying drawings, in which—

Figure 1 is a perspective view of a dummy or a regular package showing my improved display device attached thereto, the dummy or package being broken away to show construction.

Figure 2 is a view in lengthwise section through the same.

Figure 3 is a view in cross section on a plane denoted by the dotted line 3—3 of Figure 1.

Figure 4 is a front view.

Figure 5 is a perspective view of a portion of a dummy or package showing the slots provided for the reception of tongues on the display device.

It is common in the display of articles of merchandise to employ "dummies" instead of regularly filled packages, in connection with such display, although in many cases regularly filled packages are employed for the purpose, and, therefore, where the term "dummy" is employed herein it should be understood as comprising within its scope a regularly filled or unfilled package or an imitation thereof.

In the accompanying drawings the number 6 denotes a dummy of a package or carton that may be formed in any usual manner in imitation of a regular package to contain merchandise, or in place of such

dummy a regularly filled or unfilled package may be used. The material comprising such dummy is folded in various ways to secure a closed structure, as herein shown there being a slot 8 between the front 7 and a tuck 9 of the top 10, which tuck is inserted within a space between the front 7 and end flaps 11 that are inturned from the sides of the structure and underlie the top 10. Slots 12 are formed in the sides 13 of the device adjacent to the front thereof and directly opposite each other in said sides, and as shown in Figure 5 of the drawings. 65

My improved display device comprises a display disc or body 14 that may be of any suitable material and of any desired shape, this disc having slots 15 cut therethrough to provide a central or main support 16 and side supports 17 projecting from the main part or body of the disc. These slots may be of any desired form, or, in fact, they may be narrow slits. In producing these slots, for convenience in making the dies, notches 70 75 18 are created in opposite edges of the central support.

In attaching the display device or disc to a dummy or to a package or carton the central or main support 16 is slipped into the slot 8 between the front of the carton and the tuck 9, and the tongues 19 are slipped through the slots 12, the shoulders formed by such tongues catching in the ends of the slots and thus securely anchoring the 85 device. The disc is thus securely supported in an upright position and is also so secured that it is not liable to be accidentally displaced. The location of the support 16 in the slot 8 and the tongues 19 projecting 90 through the slots 12 support the disc against flatwise movement and the edges of the side supports 17 resting against the sides of the dummy or package firmly support the disc against edgewise movement, the projection of the tongues 19 through the slots and engagement with the ends thereof insuring retention of the disc in place. 95

In accordance with the provisions of the patent statutes I have described the principles of operation of my invention, together with the device which I now consider to represent the best embodiment thereof; but I desire to have it understood that the de- 100

vice shown is only illustrative, and that the invention may be carried out by other means.

I claim—

- 5 1. A display device comprising a body having slots therein arranged to provide a central support and side supports located on opposite sides of the central support, said side supports having tongues projecting 10 from the inner edges thereof for engagement in slots in a supporting structure to prevent disengagement of the central support from said supporting structure.
- 15 2. A display device comprising a body having slots therein to provide a central support and side supports on opposite sides of the central support, and shouldered holding tongues on said side supports, for engagement in slots in a supporting structure to 20 prevent disengagement of the central support from said supporting structure.
- 25 3. A display device comprising a supporting carton having slots in its walls, a display-disc adapted to rest against an outside wall of the carton and having side supports

extending along walls of the carton, and tongues projecting through said slots to prevent separation of the disc from the supporting carton.

4. A display device comprising a supporting carton having slots in its walls, a display disc adapted to rest against an outside wall of the carton and having side supports extending along walls of the carton and a central support extending within the carton, and tongues projecting through said slots to prevent separation of the disc from the supporting carton.

5. A display device comprising a supporting carton having slots in its walls, a display disc adapted to rest against an outside wall of the carton and having side supports extending along walls of the carton and a central support extending within the carton, and shouldered tongues projecting through said slots and engaging the ends thereof to prevent separation of the disc from the supporting carton.

GEORGE S. HURST.
